Primary Examiner — Mary Ann Calabrese*Assistant Examiner* — Katelin G Kloberg*(74) Attorney, Agent, or Firm* — Jeenam Park(57) **CLAIM**

The ornamental design for a under bed storage container, as shown and described.

DESCRIPTION

FIG. 1 is a front, left and top perspective view of a under bed storage container, showing my new design;

FIG. 2 is a rear, right and top perspective view thereof;

FIG. 3 is a front, right and top perspective view thereof;

FIG. 4 is a front, left and bottom perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines shown in the drawings illustrate portions of the under bed storage container that form no part of the claimed design.

1 Claim, 10 Drawing Sheets(56)
